COIN CONTROLLED VENDING
MACHINE

William H. Rowe, New York, N. Y.

Application December 23, 1933, Serial No. 703,708

3 Claims. (Cl. 312—67)

This invention relates to improvements in coin controlled vending machines.

The general object of this invention is to provide an improved coin controlled delivery mechanism for vending machines.

Another object of the invention is to provide novel means for locking the delivery plungers of a vending machine against actuation.

A further object of the invention is to provide 10 a coin controlled vending machine including a plurality of novel delivery plungers which are locked against operation by a common means and wherein when the locking means is released only one of the delivery plungers may be operated.

A still further object of the invention is to provide a vending machine including novel coin actuated means for releasing the delivery plungers and means whereby coins may be returned to 20 the operator after actuating the plunger releasing means and before the delivery plunger is operated.

Other objects and the advantages of this invention will be apparent from the following description taken in connection with the accompanying drawings wherein:

Fig. 1 is a fragmentary cross section of my improved vending machine taken on line 1—1 of Fig. 4;

Fig. 2 is a fragmentary section taken on line 2—2 of Fig. 1;

Fig. 3 is a fragmentary bottom view of a portion of the vending machine;

Fig. 4 is a fragmentary section taken on line 3—4 of Fig. 1;

Fig. 5 is a fragmentary section taken on line 5—5 of Fig. 4;

Fig. 6 is a view similar to Fig. 4 showing different positions of the various parts;

Fig. 7 is a fragmentary view similar to Fig. 4 showing the coin return mechanism in a different position;

Fig. 8 is a fragmentary section taken on line 8—8 of Fig. 4; and,

Fig. 9 is a sectional view taken on line 9—9 of Fig. 6.

This invention is an improvement over that shown in application Serial No. 623,991, filed July 22, 1932, by W. L. Gilchrist.

Referring to the drawings by reference characters I have indicated a vending machine embodying the features of my invention generally at 10. As shown this vending machine includes a housing 12 having a plurality of vertical hoppers 13 therein in which articles such as pack-

ages 14 of cigarettes are positioned and adjacent one end of the vending machine a smaller hopper 15 is provided in which boxes 16 of matches are positioned.

For removing the packages of merchandise from the hoppers 13 I provide delivery plungers 17 which are mounted in a frame 18 positioned in the housing 12 and for removing the merchandise from the hopper 15 I provide a delivery plunger 19 also mounted in the frame 18. Each of the 10 plungers 17 and the plunger 19 include a shank 20 which is positioned in a transverse groove 21 provided in the upper face of the frame 18.

The frame 18 is provided with a cover member 22 which is positioned over the plunger shanks 15 20. The forward end of each of the plunger shanks 20 is provided with an enlarged head 23 which extends out of the housing 12 through an aperture 24 provided in the front wall thereof. The plunger shank 20 extends rearwardly beyond 20 the rear face of the frame 18 and adjacent the rear of the plunger shank I provide an upstanding portion 25 which supports a horizontal platform portion 26 which extends forwardly therefrom.

In the initial position of the plunger 17 the platform portion 26 is positioned directly below the merchandise in the associated hopper and the lower package of merchandise is supported on the platform 26 (see Fig. 5). In one side and 30 adjacent the bottom of the plunger shank portion which extends towards the rear of the frame 18 I provide a plurality of saw-toothed notches 27. Adjacent the rear of the plunger shank I provide a recessed portion 28 and adjacent the rear face 35 of the frame 18 I provide a recessed portion 29 in the plunger shank 20. The recessed portions 28 and 29 are of greater depth than the height of the saw-toothed notches 27.

Extending rearwardly from the frame 18 adjacent each of the delivery plungers I provide a pair of spaced lugs 30 (see Figs. 2 and 5). The adjacent faces of each pair of the lugs 30 are provided with a recessed bearing portion 31.

Positioned between each pair of the lugs 30 I 45 provide a locking dog member 32 which includes opposed pivot bosses 33 which are positioned in the bearing recesses 31 of the lugs 30. Extending upward from the pivot bosses 33 the dog 32 includes a tapered portion 34 which in the initial position of its associated plunger is positioned in the recess 29 of the plunger. For resiliently urging the portion 34 of the dog 32 forwardly I provide a coiled spring 35, one end of which, is connected to the dog as at 36 and the opposite 55

end of which is anchored to the frame 18 as at 37. The dog 32 is provided with limiting lugs 32' on each face.

When the delivery plunger is moved forwardly 5 the portion 34 is tilted forwardly by the sides of the saw-toothed notches 27 and does not again assume its initial position until the plunger has been moved forwardly a sufficient distance to move the plunger platform 26 completely out from 10 under the merchandise in its associated hopper. Thus should the operator try to move the plunger rearwardly before completing the forward movement of the plunger the upper end of the dog 32 will wedge in one of the saw-toothed notches 27 15 and prevent rearward movement of the plunger. Similarly, when the delivery plunger is being moved rearwardly from its forward position the dog 32 will prevent forward movement of the plunger until the plunger has been returned to 20 its initial position and the upper end of the dog enters the recess 29.

When the plunger platform 26 is moved from 25 under the merchandise in its associated hopper all of the merchandise in the hopper moves downwardly and the lowermost package rests on a pair of inwardly extending side flanges 38 provided at the lower end of the hopper (see Fig. 2). When the delivery plunger is moved rearwardly the rear of the platform 26 engages the front of the lower- 30 most package of merchandise and moves it rearwardly out of the hopper through an aperture 39 provided in the rear wall of the hopper, and off the flanges 38. Whereupon the package of merchandise is directed to the customer in a manner 35 to be described hereinafter.

Below and to the rear of the hoppers 13 and 15 I provide a rod 40 which is pivotally mounted in 40 bearings 41 on the side walls of the housing 12. Mounted on the rod 40 and suitably secured thereto I provide a tray member 42. In its initial position the tray 42 is inclined forwardly and downwardly from the rod 40 and adjacent its lower end rests on the upper portion of a delivery chute 43. Adjacent one end of the rod 40 45 I secure an upstanding arm 44.

Adjacent the front of the frame 18 I provide an elongated U-shaped operating member 45 which extends at right angles to the delivery plungers. The operating member 45 is pivotally mounted 50 on and depends from a rod 46 which extends at right angles to the delivery plungers and is supported by a plurality of bosses 47 integral with the frame 18.

Pivots mounted on the rod 46 adjacent each 55 of the delivery plungers I provide an actuating dog member 48. The lower portion of each of the dogs 48 engages the front portion of the member 45 and above the rod 46 the dog includes a finger portion 49 which extends to a recess 50 provided in the shank 28 of its associated delivery plunger.

Pivots connected at one end to one of the side members of the U-shaped actuating member 45 I provide a rod 51 the opposite end of which 65 is pivotally connected to the arm 44 on the rod 40. Thus when one of the delivery plungers is moved forwardly it swings the lower end of its associated dog 48 rearwardly which in turn swings the member 45 rearwardly thereby moving the 70 rod 51 rearwardly which in turn swings the arm 44 rearwardly thereby rocking the rod 40. As the rod 40 is thus rocked the tray 42 swings upwardly to a substantially horizontal position as indicated by the broken lines in Fig. 5.

When the tray 42 is in a raised position it pre-

vents a dishonest operator from inserting a wire upward through the delivery chute and working packages of merchandise out of the hopper while its associated delivery plunger is in a forward position.

Adjacent the rear of the hoppers I provide a rod 52 which is pivotally mounted in brackets 53 secured to lugs 54 extending from the sides of the housing 12. Mounted on the rod 52 and suitably secured thereto I provide a depending apron member 55 which extends across the apertures 39 in the merchandise hoppers. At one end the rod 52 includes an upstanding portion 56 to which one end of a coiled spring 57 is connected, the opposite end of the spring being anchored to a portion of the bracket 53 (see Fig. 5). To limit the rearward movement of the portion 56 of the rod 52 I provide a stop pin 59 on the bracket 53. The apron 55 also helps to prevent a dishonest operator from inserting a wire up through the delivery chute 43 and working packages of merchandise out of the hopper.

When a package of merchandise is moved rearwardly by its associated delivery plunger as previously described the package engages the apron 55 and upon continued rearward movement swings the apron 55 upward against the action of the spring 57. When the package moves completely off the supporting flanges 38 the spring 57 through the medium of the apron 55 forces the package downward onto the tray 42 from which it slides into the delivery chute 43 which guides the package to a position wherein it is accessible from the exterior of the vending machine.

Intermediate the width of the platforms 26 35 of the delivery plungers 17 I provide a slot 60 which extends from the front face thereof rearwardly a predetermined distance. Positioned in the slot 60 I provide a bar member 61 which is pivoted intermediate its length to the platform 40 as indicated at 62 in Fig. 5. Adjacent the forward end of the bar 61 I provide an enlarged head portion 63 which includes an undercut portion 64 having an upper surface 65 and a stop face 66. The portion of the bar 61 forward of 45 the pivot 62 is heavier than the portion thereof in the rear of the pivot so that when no merchandise is supported on the platform 26 the forward portion of the bar 61 tilts downward as indicated by the broken lines in Fig. 5.

When the bar 61 is thus tilted downward the surface 65 thereof rests on the top surface of the cover plate 22. In this position the stop face 66 of the bar is below the upper surface of the cover 22 and will upon a slight forward 55 movement of the plunger engage the rear face of the cover and prevent further forward movement of the plunger. The distance the plunger moves to bring the stop face 66 of the bar 61 into engagement with the cover 22 is such that 60 the dog 32 retains its position in the recess 29.

When a package of merchandise is supported on the platform 26 the weight of the package retains the bar 61 in a horizontal position as shown in full lines in Fig. 5. When the bar 61 65 is in a horizontal position the stop face 66 thereof is above the upper surface of the cover plate 22 and the delivery plunger can be moved forwardly. When the platform is moved out from under the merchandise the forward end of the 70 bar 61 being heavier than the rear portion thereof moves downwardly into engagement with the upper surface of the cover 22.

As the plunger is returned to its initial position and the package being delivered is moved 75

out from under the packages thereabove all the packages in the hopper move downward and the new lowermost package engages the rear portion of the bar 70 and moves it downward there-

5 by swinging the head 63 of the bar upward to a position wherein the stop face 66 of the bar is above the upper surface of the cover 22.

Adjacent the rear of the frame 18 and in the upper surface thereof I provide a longitudinally extending recess 67 the bottom surface of which is flush with the upper surface of the shanks 20 of the delivery plungers 17. The recess 67 terminates in an end wall 68 before it reaches the delivery plunger 19 which is associated with the match hopper 15. The end wall 68 is in line with the left hand face of the last delivery plunger 17 associated with the cigarette hoppers 13. The opposite end of the recess 67 opens into an enlarged recess 69 provided in the upper surface of the frame 18.

Positioned in the recess 67 I provide a plurality of bars 70 and a bar 71 which are adapted to have longitudinal movement in the recess 67. The bars 70 are of such a length that in their initial position when the left hand bar 70 engages the stop wall 68 the abutting faces of the bars 70 are in line with the left hand sides of the shanks 20 of the plungers (see Fig. 4). The rear left hand corners of the bars 70 and of the bar 71 are rounded by providing annular bearing members 72 cast into the bars 70 and 71. The members 72 are made of a metal of greater hardness than the material of which the bars are made. Furthermore the rear right hand corners of the bars 70 are cut at an angle as indicated at 73.

Extending upwardly from the upper surface of the shanks 20 of each of the plungers I provide a raised cam portion 74. The forward end 40 of each of the raised cam portions terminates in a point 75 which is in line with the left hand sides of the plunger shanks 20 and curves towards the right where it merges into a tapered surface 76 which extends rearwardly a predetermined distance to the right hand side of the plunger shank. When the plungers are in their initial positions the cam points 75 are approximately flush with the rear wall of the recess 67 in the frame 18.

50 When one of the plungers 17 is moved forward the cam point 75 thereof moves into engagement with the adjacent bearing member 72 of one of the bars 70. Upon further forward movement of the plunger the raised cam portion 74 thereof moves the bar 70 which it engages towards the right whereupon all the bars 70 at the right thereof move to the right and in turn move the bar 71 to the right. When the bars 70 to the right of the operated plunger are thus moved they extend across the recesses 21 in the frame 18 whereupon should one of the plungers 17 to the right of the operated plunger be moved forward the cam point 75 thereof will engage the rear face of one of the bars 70 and prevent movement of the plunger. Should one of the plungers to the left of the operated plunger be moved forward the raised cam portion 74 thereof will engage the annular bearing portion 72 of one of the bars 70 and become wedged thereagainst. 65 This is due to the fact that the right hand end of the bar 70 which is at the left of the operated plunger engages the left face of the raised portion of the operated plunger thereby preventing movement of all the bars 70 at the left of the operated plunger.

When the operated plunger is returned to its initial position the bars 70 to the right thereof and the bar 71 are returned to their initial position as will be described hereinafter.

Spaced from the bar 71 and at right angles thereto I provide a lock bar 77 which is positioned in a groove 78 provided in the frame 18. The lock bar 77 extends rearwardly from the frame 18 and is further supported by a bracket 79 which is integral with the frame 18.

Intermediate the bar 71 and the bar 77 I provide a crank member 80 which includes a pair of arms 81 and 82 arranged at approximately right angles to each other. Adjacent the juncture of the arms 81 and 82 the crank member 80 is pivoted on the frame 18 as indicated at 83. Adjacent the end thereof the arm 81 includes a protruding annular bearing portion 84 which engages a bearing block 85 inserted in the end face of the bar 71.

The end of the crank arm 82 engages the rear wall of a recess 86 provided in the bar 71. Forward of the crank member 80 I provide a dog member 86 which is pivoted on the frame 18 as indicated at 87. To the left of the pivot 87 the 25 dog 86 includes an arm 88 the end of which is normally positioned in a recess 89 provided in the end of the crank arm 81. Below and adjacent the pivot 87 the dog includes a cam face 90 and to the right of the pivot the dog includes a depending finger portion 91 which extends below the cam face 90. One end of a coiled spring 92 is connected to the crank arm 82 as at 93 and the opposite end of the spring is connected to the dog 86 as at 94. At the right end of the bar 71 30 I provide a forwardly extending arm 95 adjacent the forward end of which I provide a dog member 96. At one end the dog 96 includes an annular bearing portion 97 which is journaled in a suitable socket 98 provided in the arm 95 of the bar 71. Adjacent the opposite end the dog 96 includes an inclined cam face 99 which normally engages the cam face 90 of the dog 86. Intermediate its length the dog 96 includes a forwardly extending arm 100 which has one end of a coiled 40 spring 101 secured thereto the opposite end of the spring 101 being anchored to the frame 18, as indicated at 102.

Rearward movement of the bar 71 is normally prevented by a pivoted locking dog 103 (Fig. 1) 50 which is normally positioned in a slot 104 provided in the bar 71. The dog 103 is in this instance shown as adapted to be operated to a released position by an arm 105 which forms part of a coin released mechanism indicated generally at 55 106. The coin release mechanism 106 is of the type shown and described in application Serial No. 702,488 filed December 15, 1933, of which I am the inventor. It will be understood however that any other type of coin released mechanism 60 may be used.

When the coin release mechanism 106 has been properly operated the lever 105 has raised the dog 103 out of the slot 104 of the lock bar 71 and a delivery plunger 17 is moved forwardly and 65 moves the bars 70 and the bar 71 to the right the bar 71 swings the crank member 80 about its pivot 83 and moves the lock bar 77 rearward. As the crank arm 81 swings towards the dog 86 the end of the dog arm 88 would engage the end of the crank member but at the same time the dog member 96 moves to the right and the free end thereof engages the finger 91 of the dog 86 and swings the end 88 thereof out of the way of the crank arm 81, as shown in Fig. 6, whereupon the 75

bar 71 is free to continue its movement to the right.

When the operated delivery plunger 17 is returned to its initial position a suitable means which will be described hereinafter, moves the lock bar 77 forward which through the medium of the crank member 80 moves the bar 71 and the bars 70 to the left to their initial positions. When the bar 77 again reaches its initial forward position the lock dog 103 again prevents rearward movement thereof until the coin release mechanism is again properly operated.

The dog 86 is an auxiliary lock member which, should the lock bar 77 lag in its return movement to its initial position, will prevent movement of the bar 71 to the right. Upon a lagging return of the bar 77 to its initial position the spring 101 will swing the free end of the dog 96 upward against a shoulder 107 provided on the forward face of the dog 86 which will prevent movement of the bar 71 to the right.

This lagging movement of the bar 77 will perhaps only occur when a dishonest operator after moving one of the plungers 17 forward grasps another plunger 17 and moves the cam point 75 thereof into engagement with the rear face of the adjacent bar 70 and prevent movement of the bars 70 and then as he returns the operated plunger to its initial position tries to let the bars 70 slowly return towards their initial position by partially releasing the pressure of the other plunger on the bar 70 and then trying to slip the other plunger in between two of the bars 70 before they are fully returned to their initial positions.

The coin actuated mechanism 105 includes a coin chute 108 which is pivoted thereto as at 109. The coins after actuating the mechanism 106 enter the coin chute 108 and come to rest on a coin tray 110 which is pivotally secured as at 112 to the underside of the bracket 79. A pin 113 extending downward from the bottom of the bar 77 is positioned in a slot 114 in the tray 110. Upon rearward movement of the bar 77 the pin 113 swings the coin tray 110 about its pivot 112 thereby moving it from under the coin chute 108 whereupon the coins fall into a coin chute 115 which conveys the coins to a suitable coin receiver.

Positioned forward of the coin chute 115 I provide a coin chute 116 which is adapted to direct coins out of the housing 12 to a coin receiver 117 from which the operator may remove them.

To swing the coin chute 108 about its pivot to direct the coins therefrom into the coin chute 116 I provide an operating bar 118 which is slideable in slots 119 and 120 provided in the frame 18. The forward end of the bar 118 is provided with an enlarged head 121 which extends out of the housing 12 through an aperture 122 provided in the front wall thereof. The bar 118 extends rearwardly from the frame 18 and is supported on the bracket 79. Adjacent its rear end the bar 118 includes a lug 123 which extends from the side thereof and engages the end of a rearwardly extending cam portion 124 on the coin chute 108.

Projecting downwardly from the lock bar 77 I provide a finger portion 125 and projecting downwardly from the bar 118 I provide a similar finger 126.

70 A coiled spring 127 having one end secured to the finger 125 and the opposite end secured to the pin 126 resiliently urges the bar 77 forward and the bar 118 rearwardly. The spring 127 returns the bar 77 to its initial position after it has been moved rearwardly, as previously described.

If an operator desires to have his coins returned to him after depositing them in the vending machine he may do so before operating one of the delivery plungers 17 by moving the bar 118 forwardly. When the bar 118 is moved forward the lug 123 thereon engages the cam member 124 on the coin chute 108 and swings the lower end of the coin chute 108 forward to the broken line position shown in Fig. 1. When the coin chute 108 is in this position the coins therein roll out of the chute 108 into the return chute 116 and thence to the receiver 117. When the operator releases the bar 118 the coiled spring 127 moves it rearwardly to its initial position whereupon the weight of the coin chute 108 swings it 15 about its pivot to its initial position.

In a raised portion 128 of the bracket 79 and adjacent the rear thereof I provide a recess 129 in which a disk 130 is positioned. In the bar 77 I provide a recess 131 and in the bar 118 I provide 20 a similar recess 132. When the bars 77 and 118 are in their initial positions the recesses 131 and 132 are positioned one on each side of the recess 129 in the raised portion 128 of the bracket 79. The ends of the recesses 131 and 132 are preferably bevelled as shown.

The diameter of the disk 130 equals the width of the raised portion 128 of the bracket 79 plus the width of one of the bars 77 or 118. When the bar 77 is moved rearwardly the disk 130 is 30 moved into the recess 132 of the bar 118 thereby preventing movement of the bar 118 and when the bar 118 is moved forwardly the disk 130 is moved into the recess 131 of the bar 77 thereby preventing movement of the bar 77. Thus when 35 one of the bars 77 or 118 is operated the other cannot be operated.

For controlling the operation of the match delivery plunger 19 I provide a pair of spaced bars 133 and 134 which are slidably mounted in recesses 135 and 136 respectively provided in the frame 18. The bars 133 and 134 extend rearwardly from the frame 18 where they are supported by a bracket 137 integral with the frame 18. The bars 133 and 134 each include stop 45 shoulders 138 protruding from opposite sides thereof which normally engage the rear faces of raised portions 139 provided adjacent the rear of the bracket 137. Extending downwardly from each of the bars 133 and 134 I provide fingers 140 50 (see Fig. 8). Each of the fingers 140 have one end of a coiled spring 141 secured thereto and the opposite ends of the springs 141 are anchored to pins 142 provided on the frame 18. The springs 141 resiliently retain the bars 133 and 55 134 in a forward position with the stop shoulders thereon engaging the raised portion 139 of the bracket 137, as shown in Fig. 4.

On the side of the bar 133 facing the bar 134 I provide a lug 143 having a downwardly and rearwardly curved surface 144. Spaced rearwardly from the lug 143 on the bar 133 I provide a lug 145 on the side of the bar 134 facing the bar 133.

The lugs 143 and 145 in combination with the adjacent sides of the bars 133 and 134 form a coin slot 146 in which a one cent coin is adapted to be inserted and the curved portion 144 of the lug 143 forms a supporting portion to retain the coin in the coin slot 146. For delivering a coin to the coin slot 146 I have shown a coin chute 70 147, the lower end of which is positioned directly above the coin slot 146 and the upper portion of which extends to a suitable point where a coin may be inserted thereinto from the exterior of the housing 12.

The forward end of the bar 133 is bevelled to form a cam surface 148 and the forward end of the bar 134 is similarly bevelled to form a cam surface 149. Normally the cam surface 148 of the bar 133 is positioned at the rear of the cam surface 149 of the bar 134 as shown in Fig. 4.

For moving the bars 133 and 134 rearwardly I provide an arm 150 which is pivotally mounted as at 151 to the frame 18. The end of the arm 150 opposite the pivot 151 includes an enlarged head 152 which includes an arcuate cam surface 153 and a working face 154. For resiliently retaining the arm 150 in a normal position as shown in Fig. 4 I provide a coiled spring 155 one end of which is connected to the arm 150 as at 156 and the opposite end of which is anchored to the frame 18 as at 157.

For moving the arm 150 I provide an operating lever 158 which is pivoted adjacent one end thereof as at 159 on the frame 18. The lever 159 includes a curved surface 160 which curves across the path of movement of the delivery plunger 19 and terminates in a rounded end portion 161. Opposite the curved surface 160 the lever includes an inclined cam face 162. The corner of the head 152 of the arm 150 at the juncture of the faces 153 and 154 normally engages the cam face 162 of the lever 158 as shown in Fig. 4.

When a one cent coin is inserted in the coin chute 147 it is conveyed thereby to the coin slot 146 formed by the bars 133 and 134. When a coin is thus deposited in the coin slot 146 the operator moves the delivery plunger 19 forward whereupon the raised portion 74 of the delivery plunger engages the curved surface 160 of the lever 158 and swings the cam face 162 of the lever towards the bars 133 and 134. Whereupon the cam face 162 of the lever 158 swings the head 152 of the arm 150 towards the bars 133 and 134.

As the arm 150 is thus moved the cam surface 153 thereof engages the cam surface 148 of the bar 133 and moves the bar 133 rearward. As the bar 133 is thus moved the coin in the coin slot 146 being in engagement with the lug 143 of the bar 133 and the lug 145 of the bar 134 moves the bar 134 rearwardly.

As the lever 158 continues to move the arm 150 towards the bar 134 the cam face 153 of the arm 150 moves into engagement with the cam face 149 of the bar 134 whereupon the bar 133 ceases to move rearwardly. Upon continued movement of the arm 150 the cam surface 153 thereof moves the bar 134 rearwardly a distance sufficiently to move the lug 145 thereon a sufficient distance from the lower end of the curved portion 144 of the lug 143 on the bar 133 to allow the coin in the coin slot 146 to fall therefrom as shown in Fig. 8. Whereupon the coin falls into a coin chute 164 which conveys the coin to a suitable receiver (not shown).

When the delivery plunger 19 is moved rearwardly to its initial position the coiled spring 155 returns the arm 150 to its initial position and the arm 150 returns the lever 158 to its initial position. At the same time the springs 141 return the bars 133 and 134 to their initial positions.

When the delivery plunger 19 is moved forwardly without a coin being positioned in the coin slot 146 of the bars 133 and 134 the operating lever 158 swings the arm 150 towards the bars 133 and 134 and moves the bar 133 rearwardly as previously described. But as no coin is positioned in the coin slot 146 the bar 134 is not moved rearwardly and as the arm 150 continues to move towards the bar 134 it engages the side of the bar

134 which prevents further movement of the arm 150 and the lever 158 and as the point 75 of the raised portion 74 on the plunger 19 has not passed off of the curved portion 160 of the lever 158 further forward movement of the delivery plunger 19 is impossible.

From the foregoing description it will be apparent that I have provided a novel vending machine mechanism which is economical in construction and highly efficient in use.

Having thus described my invention, I claim:

1. In a vending machine, a plurality of hoppers adapted to receive packages of merchandise therein, a plurality of delivery plungers movable in said vending machine and positioned one below each of said hoppers, said plungers being adapted to expel a package from said hoppers, a delivery chute positioned below said hoppers and having an entrance end into which packages expelled from said hoppers may fall, a tray member adjacent said chute entrance and adjacent the rear of said hoppers and positioned below said hoppers, said tray member being pivotally mounted and being normally inclined downward from its pivot towards said chute entrance, an operating arm connected to said tray, a U-shaped bar positioned below said plungers and extending at right angles thereto, the arms of said U-shaped bar being pivotally supported, a rod connecting said tray arm and said U-shaped bar, and means whereby upon movement of one of said plungers in a predetermined direction said U-shaped bar will be rocked and said tray arm will swing said tray upward.

2. In a vending machine, a plurality of hoppers adapted to receive packages of merchandise therein, a plurality of delivery plungers movable in said vending machine and positioned one below each of said hoppers, said plungers being adapted to expel a package from said hoppers, a delivery chute positioned below said hoppers and having an entrance end into which packages expelled from said hoppers may fall, a tray member adjacent said chute entrance and adjacent the rear of said hoppers and positioned below said hoppers, said tray member being pivotally mounted, 30

an operating arm connected to said tray, a U-shaped bar pivotally supported below said plungers, a rod connecting said tray arm and said U-shaped bar, a finger member adjacent said plungers, said finger being pivotally mounted intermediate its length, a recess in the lower surface of a plunger, the upper end of said finger being positioned in said plunger recess and the lower ends of said finger engaging one side of the longitudinal portion of said U-shaped bar whereby upon movement of said plunger said finger will be rocked and will in turn rock said U-shaped bar which through the medium of the said rod and said tray arm will swing said tray upward.

3. In a vending machine, a plurality of hoppers adapted to receive packages of merchandise therein, a plurality of delivery plungers movable in said vending machine and positioned one below each of said hoppers, said plungers being adapted to expel a package from said hoppers,

an apron pivotally mounted in the rear of said hoppers, said apron including a portion in the path of movement of an article in the hoppers, a delivery chute positioned below said hoppers and having an entrance end into which packages expelled from said hoppers may fall, a tray member adjacent said chute entrance and adjacent the rear of said hoppers and positioned below said hoppers, said tray member being pivotally

mounted and being normally inclined downward from its pivot towards said chute entrance, an operating arm connected to said tray, a U-shaped bar positioned below said plungers and extending at right angles thereto, the arms of said U-shaped bar being pivotally supported, a rod connecting said tray arm and said U-shaped bar, a finger member adjacent each of said plungers said fingers being pivotally mounted intermediate their length below said plungers, a recess in the lower surface of each of said plungers, the upper

end of said fingers being positioned in said plunger recesses and the lower ends of said fingers engaging one side of the longitudinal portion of said U-shaped bar whereby upon movement of one of said plungers in a predetermined direction said associated finger will be rocked and will in turn rock said U-shaped bar which through the medium of the said rod and said tray arm will swing said tray upward.

WILLIAM H. ROWE. 10
